(Cl. D9—2)

To all whom it may concern:

Be it known that I, Theodore A. Grohs, a citizen of the United States and resident of the city of Los Angeles, county of Los Angeles, State of California, have invented a new, original, and ornamental Design for a Vacuum Cleaner Casing, of which the following is a specification, reference being had to the accompanying drawings, forming a part thereof, in which:

Fig. 1 is a perspective view of the vacuum cleaner casing showing my new design;

Fig. 2 is a side elevation;
Fig. 3 is a front end elevation;
Fig. 4 is a rear end elevation;
Fig. 5 is a top plan view; and
Fig. 6 is a bottom plan view thereof.

I claim:

The ornamental design for a vacuum cleaner casing, substantially as shown.

THEODORE A. GROHS.
